Charles Parker's Trade Mark.

3803

PATENTED DEC 21 1869

United States Patent Office.

CHARLES PERKES, OF PHILADELPHIA, PENNSYLVANIA.

Design No. 3,803, dated December 21, 1869.

DESIGN FOR A TRADE-MARK

The Schedule referred to in these Letters Patent and making part of the same.

To all whom it may concern:

Be it known that I, CHARLES PERKES, of the city of Philadelphia, and State of Pennsylvania, have invented a new and original Design for a Trade-Mark, to be used in marking metallic wares; and I do hereby declare the following to be a full, clear, and exact description thereof, reference being had to the accompanying drawing, forming a component part of this specification.

This trade-mark consists of a circle and an ellipse of equal or nearly equal circumferences, so formed

and placed, relatively to each other, as to intersect each other at four points, as shown in the drawing. In the centre of the design thus formed, I place the words "trade-mark."

What I claim as a new and original design is—
The hereinbefore-described device for a trade-mark.

CHARLES PERKES.

Witnesses:

ANDREW MORROW,
S. LLOYD WUGAND.
